(57) **CLAIM**

The ornamental design for a dog harness, as shown and described.

DESCRIPTION

FIG. 1 is a front and side perspective view of a dog harness showing a new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing a dog in FIG. 1 depict environmental matter that forms no part of the claimed design. The broken lines on the pet harness in FIGS. 1 through 7 depict stitching that forms part of the claimed design.
